UNITED STATES PATENT OFFICE

2,653,196

MODULATING PULSATR

Ralph L. Cockman, High Point, N. C.

Application January 22, 1951, Serial No. 207,159

1 Claim. (Cl. 200—31)

1 This invention relates to a modulating pulsator for a humidifier system.

An object of this invention is to control a fixed cycle operation of varied duration.

Another object of this invention is to produce a more uniform condition, and the ability to increase or decrease the amount of water added automatically to the humidifier system.

With the foregoing and other objects in view, this invention comprises certain novel constructions, combinations, and arrangements of parts as will be hereinafter fully described, illustrated in the accompanying drawings, and more particularly pointed out in the appended claim.

In the drawings:

Figure 1 is a view in front elevation of a mechanism constructed in accordance with the present invention.

Figure 2 is a vertical, sectional view, taken on line 2—2, Fig. 1, and looking in the direction of the arrows.

Figure 3 is a vertical, sectional view, taken on line 3—3, Fig. 1, and looking in the direction of the arrows.

Referring to the drawings, in which the preferred embodiment of this invention is illustrated, 1 designates the casing. A bracket 2 is provided with flanges 3, Fig. 1, which have elongated slots 4 that have screws 5 therein; these screws are secured to the casing 1. The bracket 2 is therefore vertically adjustable upon the casing 1. An electric motor 6 is provided with ears 7, and extending through these ears are screws 8, whereby the motor is secured to the bracket 2. The motor 6 is provided with a circular eccentric cam 9.

A switch supporting arm 10 is mounted on screw 11, Fig. 3. This screw 11 extends into screw support 12, which support is secured by screw 13 to the inner face of the back of casing 1. The arm 10 is of substantially U-shape in cross section. By means of screw 14, Fig. 1, a switch 15 is secured within the arm 10. This switch 15 is provided with a springy switch trigger 15¹, and on trigger 15¹ is a shoe 16. The shoe 16 is adapted to engage cam 9, as hereinafter described.

A bolt-like pin 17 extends through the bottom of casing 1 and is held in place by means of lock nuts 18. On the pin 17 is a coil spring 19. The lower end of coil spring 19 is seated on a bushing 20, and the upper end of spring 19 is seated on bushing 21, Fig. 2, within the U-shaped arm 10. The upper end of the bolt-like pin 17 extends through the supporting arm 10, as shown. On

the bolt-like pin 17 is an adjusting nut 22, bearing against the bushing 20. A lock nut 23 is against the nut 22, whereby the tension of the coil spring 19 is retained fixed, after being adjusted.

2 A housing 24 is secured to the top of the casing 1 and this housing contains a bellows (not shown). A plunger 25 extends from the bellows into the casing 1, directly above the switch trigger 15¹. Therefore, when the bellows in housing 24 causes the plunger 25 to move downwardly, the pressure is applied to the arm 10, causing the switch trigger 15¹ to move downwardly, whereby shoe 16 presses upon the cam 9.

Lead wires 26, Fig. 1, are connected to the motor 15 and lead wires 27 are connected to the switch 15, and lead wires 28 are connected to the electrically operated three-way solenoid valve 29; this solenoid valve is attached to one side of the casing 1, as shown. By means of these lead wires, the different elements of this mechanism are supplied with the needed electric current. Of course, these lead wires are in circuit with a suitable source of electricity.

The modulating pulsator is a device to control a fixed cycle operation of varied duration. A normally opened circuit will operate as follows: The eccentric cam 9 is driven by the motor 6 at a predetermined speed R. P. M. With no air pressure on the bellows in housing 24, the spring 19 will move switch arm 10, causing switch 15 to move, which in turn will take switch trigger 15¹ and cam shoe 16 out of range of cam 9, causing electrical contact in the switch to stay open. On application of air pressure to the bellows in housing 24, the bellows plunger 25 pushes down on arm 10 to balance point with loading spring 19. This puts switch trigger 15¹ in contact with eccentric cam 9, tripping switch 15 and making electrical contact for a given part of cam cycle, for instance, one-third of cycle. Or a further increase of air pressure on the bellows will cause a new position to be taken by trigger 15¹ through above movement, causing a contact of longer duration, for instance, one-half of a cam cycle. A greater increase of air pressure on the bellows will cause a continuous contact. Lowering of the air pressure on the bellows will have the opposite effect, or to shorten the duration of contact.

While I have described the preferred embodiment of the invention and illustrated the same in the accompanying drawings, certain minor changes or alterations may appear to one skilled in the art to which this invention relates during the extensive manufacture of the same, and I,

therefore, reserve the right to make such changes or alterations as shall fairly fall within the scope of the appended claim.

What I claim is:

In a modulating pulsator, a housing, an arm of U-shaped cross section in said housing, a pivotal mounting for one end of said arm, a compression spring abutting the other end of said arm and seating within the bight thereof, a pressure-responsive plunger abutting said arm at an intermediate point on the side opposite said spring, a contact carried by said arm on the side opposite said plunger, an eccentric rotatably mounted in said housing adjacent said contact, said eccentric comprising a second contact, electrical means associated with said first and second contacts whereby upon engagement of said first contact with said eccentric a circuit is closed, means for rotating said eccentric at a constant speed,

10

15

and means for varying the pressure exerted by said spring whereby to vary the pressure required to be exerted by said plunger to maintain said first contact in engagement with said eccentric for a predetermined portion of each arc of rotation thereof.

RALPH L. COCKMAN.
